Primary Examiner — T. Chase Nelson*Assistant Examiner* — Mark Cavanna(74) *Attorney, Agent, or Firm* — James E. Howard; Andre Pallapies(57) **CLAIM**

The ornamental design for an accessory for cooking appliance, as shown and described.

DESCRIPTION

FIG. 1 is a front perspective view of an accessory for cooking appliance according to our new ornamental design;

FIG. 2 is a front view thereof;

FIG. 3 is a right side view thereof;

FIG. 4 is a rear view thereof;

FIG. 5 is a left side view thereof;

FIG. 6 is a bottom view thereof; and,

FIG. 7 is a top view thereof.

The broken lines are included for the purpose of illustrating portions of the accessory for cooking appliance that form no part of the claimed design.
